UNITED STATES PATENT OFFICE.

OLIVER H. STUCKWISCH, OF INDIANAPOLIS, INDIANA.

AUTOMOBILE-HEATER.

1,262,282.

Specification of Letters Patent. Patented Apr. 9, 1918.

Application filed February 7, 1916, Serial No. 76,670. Renewed March 8, 1918. Serial No. 221,330.

To all whom it may concern:

Be it known that I, OLIVER H. STUCKWISCH, a citizen of the United States, residing at Indianapolis, in the county of Marion and State of Indiana, have invented new and useful Improvements in Automobile-Heaters, of which the following is a full, clear, concise, and exact description, reference being had to the accompanying drawing, forming a part of this specification.

My invention relates to automobile heaters.

Among the objects of my invention is to provide an improved automobile heater in which the heat can be easily and definitely regulated, and which will utilize a large portion of the heat in the exhaust gases which pass through the heater.

Further objects will appear from the detailed description to follow taken in connection with the appended claims.

In the drawings in which I have shown two embodiments of my invention—

Figure 1 is a side elevation of an automobile, parts being broken away to show the location and arrangement of the heater;

Fig. 2 is a section on the line 2—2 of

Fig. 3;

Fig. 3 is a plan view of the heater, parts being broken away to show the interior construction;

Fig. 4 is a section on the line 4—4 of Fig. 3;

Fig. 5 is a section on the line 5—5 of Fig. 2; and

Fig. 6 is a section on the line 6—6 of Fig. 2.

Referring now to the drawings in detail, I have shown my invention in connection with an automobile 8 having an internal combustion engine 9 provided with an exhaust manifold 10 leading to the exhaust pipe 11. The floor 12 of the automobile is provided with an opening 13 in which is located the heater. This heater comprises a casing or container 14 which fits in the opening 13 and contains a radiator 15 which is in communication with the exhaust pipe 11 through an upwardly and rearwardly inclined inlet conduit 16 and an outlet conduit 17 which extends rearwardly in the same horizontal plane of the radiator. Communication between the exhaust pipe 11 and the inlet conduit 16 is controlled by means of a forwardly projecting flap valve 18 to regulate the quantity of gas flowing through

the radiator. The casing 14 is provided with a cover 19 having a plurality of openings 20 therein for the escape of the heated air. The bottom of the casing 14 is provided with 60 openings 21 and 22 for the inlet and outlet conduits 16 and 17, respectively. Air to be heated is supplied from the interior of the automobile to the interior of the casing through openings 22^a and a passage 22^b, 65 formed by a wall 13^a depending from the top of the casing intermediate the end wall of said casing and the radiator. The radiator 15 has a central wall or web 23 whereby a 70 U shaped passage for the hot gases is formed which continues in the same horizontal plane throughout the radiator as shown in Fig. 3. In this passage are located a plurality of baffle pins or plates 24 against which the hot gases impinge causing these 75 plates to become heated and thus utilize a large portion of the heat in the gases. Nipples 25 and 26 lead to and from the U-shaped passage and are in communication with the 80 conduits 16 and 17, respectively. The conduits 16 and 17 are connected with the exhaust pipe 11 by means of fittings 28 and 27 respectively.

The fitting 27 comprises a saddle portion 29 fitting the side of the exhaust pipe, a 85 clamping yoke 30 engaging the lower side of the exhaust pipe, bolts 30^a connecting the saddle and yoke portions, and a curved tubular portion 31 in communication with the conduit 17 and with the opening 32 in the 90 side of the exhaust pipe.

The fitting 28 comprises a semi-cylindrical portion 33 fitting the upper side of the exhaust pipe and provided with a flat upper side, a semi-cylindrical portion 34 fitting 95 the lower side of the exhaust pipe, bolts 35 connecting the portions 33 and 34 and a flat cap portion 36 fitting on top of the portion 33 and provided with a nipple 37 in communication with the conduit 16. The portions 33 and 36 are provided with registering half bearings in which is rotatably mounted a rock shaft 38 to which the flap valve 18 is secured. The upper side of the exhaust pipe and the semi-cylindrical portion 33 are provided with registering openings 39 and 40 through which the exhaust pipe is in communication with the conduit 16, the openings 39 and 40 being just large enough to permit the valve 18 to operate and lie flat therein. The valve 18 is operated by 105 means of a crank arm 41 secured to the rock

shaft 38 by means of a set screw 41^a, a link 42 pivoted to the arm 41, and a lever 43 to which the link 42 is pivoted, located in a position where it can be conveniently operated by an occupant of the vehicle.

The radiator 15 is supported in the casing 14 by means of lugs 44 which rest on the bottom of the casing.

The use and operation of my improved device is as follows: When the engine is running the exhaust gases escape through the manifold 10 and exhaust pipe 11. By adjusting the valve 18 by means of the lever 43 a portion of the exhaust gases can be deflected through the conduit 16 to the radiator 15 where they will strike against the baffle plates 24 and heat the radiator causing the air within the casing 14 to become heated and causing the heated air to escape upwardly through the openings 20 to be replaced by cooler air through the openings 22^a. The valve 18 can be set to deflect any desired proportion of the exhaust gases through the radiator.

It will be observed from inspection of Fig. 2 of the drawing that the gases are exhausted from the radiator in approximately the horizontal plane of the radiator, and the intake from exhaust pipe 11 is considerably below the horizontal plane of the radiator; consequently, when the valve 18 is operated to deflect a portion of the gases from the exhaust pipe 11 into the intake, the portions of the gases not deflected will be forced along the exhaust pipe 11, and, owing to the short vertical connection at the exhaust end of the radiator, the passing gases will tend to cause a vacuum at the exhaust end of the radiator which will pull the deflected gases rapidly through the radiator, thereby securing a maximum of heat units and at the same time appreciable resistance to the engine exhaust. In other words, this construction provides an arrangement of parts to create a greater suction at the exhaust end of the radiator than at the intake end, and this is accomplished by connecting the exhaust pipe of the radiator to exhaust pipe 11 near to the horizontal plane of the radiator and connecting the intake pipe to exhaust pipe 11 considerably below the plane of the radiator. To further facilitate the rapid passage of the gases through the radiator, intake pipe 16 and its connections are inclined rearwardly from pipe 11 to the radiator, so that when the valve 18 is adjusted to deflect a portion of the gases from pipe 11, the flow of the deflected gases will be in the general direction of the main exhaust.

Another important feature of the invention is the relatively long flap valve 18 which

is hinged or pivoted at its upper end to the upper and rear side of the pipe 11 and intake 16. As thus formed and when it is positioned to deflect a portion of the gases 65 to the radiator, it effectually closes a portion of the area of the pipe 11 and forms an inclined bottom in continuation of the intake passage. When this valve closes the intake passage, it lies at the top of the pipe 11 and does not restrict the normal area of said pipe.

Having thus described my invention what I claim as new and desire to secure by Letters Patent is;

1. The combination with an exhaust pipe of an automobile, of a radiator having a continuous horizontal passage therethrough, an inlet conduit connecting one side of the radiator to said exhaust pipe and inclining 80 upwardly and rearwardly from said exhaust pipe to said radiator, an outlet conduit connecting the other side of said radiator to said exhaust pipe and extending rearwardly from said radiator to said exhaust pipe, the 85 connection of said outlet conduit with said exhaust pipe being substantially in the horizontal plane of the radiator and nearer to the horizontal plane of the radiator than is the connection of the inlet conduit with the 90 exhaust pipe, and means for deflecting a portion of the gases from said exhaust pipe into said inlet conduit.

2. The combination with an exhaust pipe of an automobile, of a radiator having a 95 continuous horizontal passage therethrough, an inlet conduit connecting one side of the radiator to said exhaust pipe and inclining 100 upwardly and rearwardly from said exhaust pipe to said radiator, an outlet conduit connecting the other side of said radiator to said exhaust pipe and extending rearwardly from said radiator to said exhaust pipe, the connection of said outlet conduit with said exhaust pipe being substantially in the horizontal plane of the radiator and nearer to the horizontal plane of the radiator than is the connection of the inlet conduit with the 105 exhaust pipe, and means for deflecting a portion of the gases from said exhaust pipe 110 into said inlet conduit, said means being adapted to project forwardly in said exhaust pipe and form an inclined bottom in continuation of the inclined inlet conduit.

In witness whereof, I have hereunto subscribed my name in the presence of two witnesses.

OLIVER H. STUCKWISCH.
